UNITED STATES PATENT OFFICE.

WALTER C. GOODWIN, OF EVANSVILLE, INDIANA.

COMBINATION SCAFFOLD BRACKET.

Application filed June 23, 1926. Serial No. 118,017.

This invention relates to a combination scaffold bracket of that class which is adapted to be supported from the side of a building and to serve as a support for one end of a 5 plank or planks to be used as a platform by a carpenter, painter, or other artisan.

The present improvements relate more particularly to means whereby the supporting legs may be connected to different points 10 of the length of the horizontal bar; and to means on the bar comprising a novel adjustable attachment, enabling the bracket to be used as a window bracket and supported from the window stool and for the utilization 15 of the bar by the hanger or bail by which the legs are supported from the horizontal bar, or, for the use of the hanger or bail alone in connection therewith when the bar is engaged with the studding.

20 The present improved bracket is preferably provided with a hook on the rear end of the horizontal bar to engage the studding of the building when the bracket is used as a studding bracket. When this use of the bracket 25 occurs, a part of the improvements, namely the notches which are provided in the horizontal bar, are utilized by the bail or hanger to maintain it in locked position. On the other hand, when the bracket is used as a 30 window bracket, the improved attachment is adapted to lock with any notch that is selected and to bear against the window stool, so that it is unnecessary to use the hook on the horizontal bar. When the hook is used to engage 35 a piece of studding, the attachment may be taken off or disengaged from the notches as it is then not needed.

The horizontal bar is provided with several holes which are used in connection with 40 the bolt for attaching the legs to the bar, one hole or another being employed for that purpose, according to the use to which the bracket is put as, for instance, when it is used with a four-inch studding or a six-inch 45 studding or in connection with the stool of a window; in which latter instance the improved attachment is used, being engaged with the window stool and locked by the notches in the bar.

50 The embodiment of the improvements entering into the present invention hereinafter described, and shown in the accompanying drawings, has been found in practice to meet all requirements of a combination scaffold bracket but I wish it understood that modi-

fications may be resorted to without departing from the principle of the invention.

In the accompanying drawings:

Figure 1 is a perspective view of the bracket when used in connection with a four-inch studding. 60

Figure 2 is a similar view showing the bracket used as a window bracket.

Figure 3 is a side elevation illustrating the use of the bracket in connection with a 65 four-inch studding.

Figure 4 is a side elevation of the bracket when used as a window bracket.

Figure 5 is a detail side view of the improved attachment. 70

Figure 6 is a detail plan view showing how the hook on the bar engages the studding, and

Figure 7 is a detail plan view showing the use of the bracket in connection with a window. 75

The bar 1 is the part of the bracket which is disposed in general horizontal position when the bracket is in use, this bar serving as a support for a plank or planks or platform on which the carpenter, painter, or other artisan stands when the bracket is applied to the studding, window stool, or side of the building or structure on which the bracket is used. Two or more of these brackets will be used to support the planks or platform. 80

The bar 1 is provided at its outer end with an upturned part or projection 2 which prevents the planks or platform from slipping off the end of the bar. At the inner end of the bar there is a hook 3 which is adapted to engage the studding of the building, such studding being shown at 4, if the bracket is used as a studding bracket. On the other hand, if the bracket is used as a window bracket, my improved attachment 5 is used and then is made to engage with the window stool 6 as will be more fully explained hereinafter. 90

The bar 1 has three holes 7, 8, 9 which are for the reception of a bolt 10 to connect the legs 11, 12 to the bar in one position or another, according to the use to which the bracket is put.

In Fig. 1 when the bracket is used as a studding bracket with a four-inch studding, the bolt 10 is entered in the hole 9. When the bracket is used with a six-inch studding, the bolt 10 is entered in the hole 8. 95

On the other hand, when the bracket is used as a widow bracket, the attachment 5 100

then engages the window stool 6, and the outermost hole 7 receives the bolt 10.

The legs 11, 12 diverge from the point where they are connected to the bar 1 by the bolt 10 to their lower ends where they are provided with feet 13. Preferably, these legs are of angle iron for the purpose of strength. Their divergence causes the bracket to be held in position with rigidity so that there is no substantial tendency to shift laterally. A cross bar 14 of angle iron is secured to the legs 11, 12 in the region of the feet 13 and braces said legs.

A suspension bail or hanger 15 which, in the present instance, is an inverted V shaped rod, has its loop 16 straddling the bar 1 and its ends 17 bent, passed through holes 18 in the webs of the legs, and bent down or clinched as shown at 19. As the bail or hanger 15 straddles the bar 1, it may assume different positions along said bar as illustrated, for instance, in Figs. 1, 2, 3, 4. The hanger suspends the divergent lower ends of the legs 11, 12 from the bar so that there is no possibility of downward slippage of the legs and, at the same time, there is an even distribution of the weight in respect to the two legs.

The upper edge of the bar 1 is provided with notches 20 of a number sufficient to accommodate the attachment 5, according to the width or thickness of the window stool 6 as shown in Figs. 2 and 4, or to be utilized by the hanger or bail 15 as illustrated in Figs. 1 and 3.

I am aware that the principle involved in the suspension of the legs 11, 12 by the hanger 15 is not dependent on the employment of the one-piece V shaped hanger which is illustrated and I do not limit the invention to the particular form of hanger 15 which is shown and described as the legs may be suspended from the bar 1 in other ways in a bracket embodying my improvements. Modified forms of hangers for the legs 11, 12 may be provided with means to engage the notches 20.

My improved attachment 5 comprises an inverted L shaped or angular clamp having a cross pin, bolt, rivet, or member 21 which is adapted to drop into one of the notches 20 to secure said attachment in any one of several positions so that the attachment may be properly placed to cooperate with the inside of the window stool 6. The adjustment thus provided along the length of the rear end of bar 1 permits use of the bracket in connection with window stools of different depths. As shown, the attachment 5 comprises two angular or L shaped pieces 5^a which are spaced apart so that they may straddle the bar 1 and they have between them a piece 5^b which is bolted or riveted thereto as shown at 22. The upper end of the piece 5^b is rounded as shown at 23 to provide the necessary clearance to enable the attachment to be freely

tilted when shifting the attachment along the bar 1 to position the cross piece, bolt or rivet 21 in the proper notch 20 so that the attachment may be located to engage the inner face of the window stool 6. On the other hand, the reactionary pressure against the vertical part of the attachment 5 causes the member 21 to be held down in the notch and the squared or straight part 24 of the piece 5^b to abut against the lower edge of the bar 1. The construction is such that the attachment 5 may be turned in one direction to release it but it cannot be turned in the other direction and it may also be entirely removed by slipping it along the bar 1. For instance, in Figs. 1 and 3 where the hook 3 is engaged with the studding, the attachment 5 appears although it is unnecessary and it is simply slipped along the bar 1 as shown by full lines in Figs. 1 and 3 to thus be in readiness for use when the bracket is used as a window bracket, or, the attachment 5 may be removed when the bracket is used as a studding bracket.

What I claim is:

1. In a scaffold bracket, the combination with a bar adapted for general lateral disposition when in use and having a plurality of notches in the region of the rear end thereof, of supporting legs for the bar adapted to be engaged therewith at different points of the outer end thereof, and a hanger for suspending said legs from said bar, said bar being shiftable laterally to different positions in relation to said hanger and said hanger having means adapted to engage the notches selectively according to the position of said bar.

2. In a scaffold bracket, the combination with a bar adapted for general lateral disposition when in use and having a plurality of notches in the region of the rear end part thereof and provided with a plurality of holes in the region of the other end thereof, of supporting legs having means to engage different ones of said holes, and a hanger for suspending said legs from said bar, said bar being adjustable laterally to different positions in relation to said hanger and said hanger having means to engage the notches selectively according to the position of the bar.

3. A combination scaffold bracket comprising a bar, means for supporting the bar from a building, means adapted for locking engagement with the bar for suspending said supporting means from said bar, an attachment adjustably mounted on the bar to enable it to be moved to different positions and to be secured where adjusted, said attachment being adapted to be secured in position to hold the bar in position on a window stool of the building or structure on which the bracket is used, and means on the bar to engage studding on the building or structure, whereby the last named means or the ad-

justable attachment may be used selectively for the connection of the bracket to the building, according to the use made of said bracket.

4. In a combination studding and window bracket, the combination with a bar provided with a plurality of notches extending from a point near the inner end of the bar toward the outer end thereof, of an attachment slidably and rockably mounted on said bar having means to engage different ones of said notches, said attachment being adapted to engage a window stool of the building when the bracket is used as a window bracket, supporting legs for the bar, and a hanger for suspending said legs from the bar and having means adapted to engage the different notches when the bracket is used as a studding bracket.
- 10
- 15

5. In a combined studding and window bracket, the combination with a bar provided with a plurality of notches extending from a point near the inner end of the bar toward the outer end thereof, of an inverted L-shaped attachment slidably and rockably mounted on the bar and adapted to lock with one of the notches when engaged with a window stool of the building on which the bracket is used, or to be released from locking engagement with the bar when said attach-
- 20
- 25

ment is tilted, supporting legs for the bar, and a hanger for suspending said legs from the bar and having means adapted to engage the different notches when the bracket is used as a studding bracket.

6. In a foldable window bracket, the combination with a bar, of supporting legs pivotally connected thereto, a hanger which suspends the legs from the bar when the bracket is in use and is adapted to slide along the bar when the bracket is being folded, and an attachment adjustably mounted on the bar for movement therewith and adapted to lock therewith at different points thereof and for engagement with a window stool when thus locked to the bar.

7. In a foldable window bracket, the combination with a bar, of supporting legs pivotally connected thereto, a hanger which suspends the legs from the bar when the bracket is in use and is adapted to slide along the bar when the bracket is being folded, said bar being provided with notches, and an attachment slidably mounted on the bar and adapted to lock selectively with the notches for engagement with a window stool.

In testimony whereof I affix my signature.

WALTER C. GOODWIN.
